UNITED STATES PATENT OFFICE.

JOHN P. PETH, OF CHICAGO, ILLINOIS.

MACHINE FOR SWAGING OR BENDING SHEET METAL.

Application filed December 5, 1923. Serial No. 678,762.

This invention relates to machines for bending or turning or spinning over the edge of sheet metal, and more particularly to machines for doing this after the different parts of some article of manufacture have been assembled together, thereby to hold the sheet metal portion in place.

Generally stated, the object of the invention is to provide a simple and effective machine for bending or turning over the circular edge of a sheet metal portion, of some article of manufacture, such as an incandescent electric lamp bulb, thereby to secure the sheet metal portion in place.

More specifically considered, the object of the invention is to provide a machine especially adapted for doing work of this kind, in connection with the manufacture of electric lamp bulbs, whereby the bulb is held stationary while the work is being done, so that the filament of the lamp will not be broken, and whereby certain other advantages will be obtained in connection with the manufacture of electric lamp bulbs or similar articles, as will hereinafter more fully appear.

It is also an object to provide certain details and features of construction tending to increase the general efficiency and the desirability of a sheet metal bending or crimping or swaging machine of this particular character.

To the foregoing and other useful ends the invention consists in matters hereinafter set forth and claimed and shown in the accompanying drawings in which—

Figure 1 is a side elevation of a sheet metal bending or crimping or swaging machine embodying the principles of the invention.

Figure 2 is an enlarged vertical section of said machine.

Figure 3 is a horizontal section on line 3—3 in Figure 2.

Figure 4 is an enlarged section of the chuck for holding the electric lamp bulb, showing the operation of bending or swaging the edge of the sheet metal sleeve on the base of the bulb, thereby to secure this sleeve in place.

As thus illustrated, the invention comprises a suitable body 1 having a vertical tubular member 2 therein, said tubular member having an enlarged portion 3 at its upper end, which portion is provided with a

freely rotated pulley 4 having a flange 5 at its upper end. This pulley rests on the base

or body 1, as shown, and the tube 2 is fixed in said body 1, and a vertically movable stem 6 is movable up and down in the tubular member 2, by means of a chain 7 attached to the lower end thereof and leading to a foot treadle (not shown) or any other suitable means. A spring 8 is suitably applied to hold the stem 6 in normally raised position, and the upper portion of this stem 6 is enlarged to form a chuck 9 having vertical slots 10 as shown. The screw member 11 is inserted downward in the chuck, as shown, to receive the lower end of the base of the lamp bulb, being adjustable for lamps of different sizes. The inner edge of the enlargement 3 is beveled at 12, and the chuck is beveled at 13, and the result is that when the stem 6 is pulled downward the chuck is contracted or pushed inward by the bevel 12, so that the chuck will grip the base of the lamp bulb as shown in Figure 4, thus securely holding the lamp in position.

The rotating flange 5 is provided with arms 14 pivoted thereon at 15, these arms having springs 16 to normally hold each arm against its stop 17, these stops being adjustable to regulate the positions of the arms, whereby said arms are tangentially arranged. Each arm has a bending or swaging roll 18 to engage the brass sleeve 19 of the lamp bulb, and each arm has a more or less conical roller 20 for engagement with the groove 21 on the bottom of the plate 22, which latter is supported by springs 23 arranged on the vertically disposed pins or rods 24 which are mounted to slide up and down in the body 1, in a manner that will be readily understood. The plate 22 has a central opening 25 through which to insert the lamp into the chuck and has a circular groove 26 for the nuts of the pivot bolts 15, as shown. An upper plate 27 is loosely hinged at 28 on the upper portion of the standard 29, which latter is secured at its lower end on the body of the machine. This plate 27 has a central opening 30 through which to insert the lamp bulb into the chuck, and has its other end provided with a chain 31 leading downward to a foot treadle, or

some other means, for pulling the plate downward. Bearing points 32 are provided on the bottom of the plate 27 to bear upon the top of the plate 22, thereby to force the latter downward. The relative arrangement is such that the groove 21 strikes the rollers 20 and thereby forces the arms 14 around

to the position shown in dotted lines in Figure 3, thereby to communicate or transmit power to force the swaging means 18 positively against the sheet metal. This moves the crimping or swaging rolls 18 into operative position, and causing the upper circular edge of the sleeve 19 to be bent or swaged over as shown in Figure 4, thus securing the brass sleeve 19 on the base of the lamp in 10 the desired manner, the plate 27, of course, is held against rotation, so that the controlling means do not rotate with the swaging means. It will be seen that the rolls 18 have a suitable peripheral formation for this purpose, as shown in Figure 4, so that the upper edge of the portion 19 is bent or swaged over and turned down to form an inwardly extending flat flange on the base of the lamp.

When the plate 27 is released, the springs 20 23 will raise the plate 22, and the arms 14 will assume their normal positions, so that the rolls 18 will disengage the lamp bulb. Then when the pull on the chain 7 is relaxed, the chuck 9 will release the lamp, and the 25 latter can then be removed upwardly through the openings 25 and 30, and another lamp can be placed in the machine for similar treatment.

It will be seen that the lamp is held stationary in a very rigid and secure manner, and is not rotated or moved around, whereby there is no danger of breaking the filament of the lamp. The means for swaging or crimping or spinning over the edge of the 30 brass sleeve of the lamp operate very quickly and effectively, under manual control, and the power necessary for driving the pulley 4 can be of any suitable character. When the pull on the chain 7 is relaxed, the spring 40 8 forces the stem 6 upward, thus causing the chuck 9 to release the lamp bulb.

The construction shown and described is 45 illustrative of the invention, and it is obvious that the construction can be changed or modified, in different ways, without departing from the spirit of the invention. It will be seen, for example, that the posts or uprights 24 can be arranged in any suitable manner, and that the machine may involve 50 two or more of these posts, or any suitable number, but for convenience of illustration two are shown, in the manner illustrated. It is also obvious that any suitable or desired 55 number of rolls 18 may be employed, without departing from the spirit of the invention.

Spring pressed elements 33 can be mounted in the body 1, to press against the bottom 60 of the pulley 4, to frictionally support the driving means, in order to present enough friction to stop the pulley promptly when the power is disconnected therefrom. These elements 33 yield in a downward direction, it will be seen, when a downward pull is exerted on the chain 7, thus cushioning the

action more or less. Also, it will be seen that stops 34 are preferably provided on the top of the disk or flange 5 to engage the arms 14, thereby to limit the movement of the swaging rolls 18 toward the work, in a manner that will be readily understood. These stops, like the stops 17, are adjustable to regulate the action of the swaging rolls.

It will be seen that the instrumentalities for controlling the swaging means do not 70 rotate, inasmuch as the controller plate 22, having the raceway 21 therein, cannot rotate, but is held against rotation. Thus the swaging rolls have pivoted levers provided with means, such as the tapered roll 20, for engaging the beveled raceway that forms part of the controlling instrumentalities, in the manner explained. Thus the swaging rolls are 75 positively forced against the articles to be operated upon, by manual power, as explained, or in any suitable way, and are withdrawn from engagement with the work by spring power applied in the manner 80 shown and described.

What I claim as my invention is—

1. In a machine for bending or swaging sheet metal, the combination of a holding device to hold the article to be operated upon, instrumentalities having means to engage the sheet metal to be operated upon, a 90 rotary support forming driving means to rotate said instrumentalities, controlling means for said holding device, and controlling means for said instrumentalities, having engagement therewith but held against rotation, adapted by movement bodily toward said article and said engaging means to transmit motion to positively force said instrumentalities against the sheet metal, whereby said instrumentalities may be rendered operative or inoperative at will, while the machine is in operation, said instrumentalities and controlling means therefor comprising a rotary member provided with a plurality of pivoted arms arranged tangentially, swaging rolls on the ends of said arms to form means for engaging the sheet metal to be swaged or bent, springs for holding said arms normally away from the work, stops to limit the movement of the swaging rolls away from the work, conical rolls on 100 said arms, a plate overlying said arms and provided with a circular groove to engage said conical rolls to force said swaging rolls into engagement with the work, and means for forcing said plate downward, forming 105 the controller therefor.

2. In a machine for bending or swaging sheet metal, the combination of a holding device to hold the article to be operated upon, instrumentalities having means to engage the sheet metal to be operated upon, a rotary support forming driving means to rotate said instrumentalities, controlling means for said holding device, and control- 115 120 125 130

ling means for said instrumentalities, having engagement therewith but held against rotation, adapted by movement bodily toward said article and said engaging means to transmit motion to positively force said instrumentalities against the sheet metal, whereby said instrumentalities may be rendered operative or inoperative at will, while the machine is in operation, said holding device comprising a chuck having means therein which are movable axially to grip the article to be operated upon, whereby the article is held stationary, and said chuck having an outer stationary portion which forms the axis of rotation for said rotating instrumentalities which perform the swaging operation, and for said driving means.

3. In a machine for bending or swaging sheet metal, the combination of a holding device to hold the article to be operated upon, instrumentalities having means to engage the sheet metal to be operated upon, a rotary support forming driving means to rotate said instrumentalities, controlling means for said holding device, and controlling means for said instrumentalities, having engagement therewith but held against rotation, adapted by movement bodily toward said article and said engaging means to transmit motion to positively force said instrumentalities against the sheet metal, whereby said instrumentalities may be rendered operative or inoperative at will, while the machine is in operation, said instrumentalities and driving means therefor comprising a pulley rotatable about said holding device as an axle, and swaging rolls movably mounted on said pulley, said controlling means for said instrumentalities overlying said rolls and having provisions for causing the rolls to move toward and away from the work.

4. In a machine for bending or swaging sheet metal, the combination of a holding device to hold the article to be operated upon, instrumentalities having means to engage the sheet metal to be operated upon, a rotary support forming driving means to rotate said instrumentalities, controlling means for said holding device, and controlling means for said instrumentalities, having engagement therewith but held against rotation, adapted by movement bodily toward said article and said engaging means to transmit motion to positively force said instrumentalities against the sheet metal, whereby said instrumentalities may be rendered operative or inoperative at will, while the machine is in operation, said holding device comprising a chuck adapted and formed to grip the base portion of an electric lamp bulb, said last mentioned controlling means having an opening therein for said bulb, and said instrumentalities comprising means disposed in position to engage a sheet metal sleeve on the base of the bulb,

at a point a distance above the lower end of said base.

5. In a machine for bending or swaging sheet metal, the combination of a holding device to hold the article to be operated upon, instrumentalities having means to engage the sheet metal to be operated upon, a rotary support forming driving means to rotate said instrumentalities, controlling means for said holding device, and controlling means for said instrumentalities, having engagement therewith but held against rotation, adapted by movement bodily toward said article and said engaging means to transmit motion to positively force said instrumentalities against the sheet metal, whereby said instrumentalities may be rendered operative or inoperative at will, while the machine is in operation, said holding device comprising a chuck for gripping the base portion of an electric lamp bulb, said last mentioned controlling means having an opening therein for said bulb, and adjustable means in said chuck to engage the lower end of the lamp base, whereby to accurately position the upper portion of the base for the operation of said instrumentalities thereon.

6. In a machine for bending or swaging sheet metal, the combination of a holding device to hold the article to be operated upon, instrumentalities having means to engage the sheet metal to be operated upon, a rotary support forming driving means to rotate said instrumentalities, controlling means for said holding device, and controlling means for said instrumentalities, having engagement therewith but held against rotation, adapted by movement bodily toward said article and said engaging means to transmit motion to positively force said instrumentalities against the sheet metal, whereby said instrumentalities may be rendered operative or inoperative at will, while the machine is in operation, in combination with spring pressed means to frictionally support and retard the rotation of said driving means, tending to press said driving means toward said last mentioned controlling means.

7. In a machine for bending or swaging sheet metal, the combination of a holding device to hold the article to be operated upon, instrumentalities having means to engage the sheet metal to be operated upon, a rotary support forming driving means to rotate said instrumentalities, controlling means for said holding device, and controlling means for said instrumentalities, having engagement therewith but held against rotation, adapted by movement bodily toward said article and said engaging means to transmit motion to positively force said instrumentalities against the sheet metal, whereby said instrumentalities may be rend-

ered operative or inoperative at will, while the machine is in operation, in combination with stops to limit the movement of said instrumentalities toward the article to be operated upon, disposed in a plane between said driving means and said last mentioned controlling means.

8. A machine for performing work on articles of manufacture, comprising engaging means for doing the required work on the articles, a rotating table forming supporting and driving means to revolve said

engaging means about the articles, controlling instrumentalities movable bodily toward said driving means and table and engaging means and thereby operative to positively force said engaging means against the articles, having engagement therewith but held against rotation, and a holder for said articles, having springs between the driving means and the controlling instrumentalities and operative to disengage the engaging means from the work.

JOHN P. PETH.
